Application April 5, 1956, Serial No. 576,492

19 Claims. (Cl. 150—49)

This invention relates to improvements in collapsible service baskets and more particularly, to strong and durable service baskets of relatively light weight, which may be readily collapsed for stacking when not in use, and which may be easily extended for normal usage.

Collapsible service baskets made in accordance with this invention are particularly designed for the use of customers in carrying merchandise to pay-counters of self-service stores, such as self-service food, drug, hardware, novelty, or department stores, and provide a less expensive and more convenient means for transporting selected merchandise in self-service stores than is provided by the relatively expensive and cumbersome push-carts in general use.

Service baskets constructed in accordance with this invention comprise a collapsible receptacle body having a bottom and enclosing side and end walls formed from canvas, textile fabric, plastic, or other flexible sheet material. The top of the receptacle body is shaped by a rigid top frame which is secured to or may be contained within a tubular loop formed in the upper portion of the flexible side and end walls. A pair of frame assemblies are pivotally connected to the top frame of the receptacle body and each comprises a handle part and a body stretcher part. The stretcher parts provide supplemental framing operative to maintain the receptacle in expanded and erect position when the handle parts are manipulated into the carrying position, but which permit collapse of the receptacle body when the handle parts are manipulated in the opposite direction. The supplemental frame assemblies are constructed from relatively stiff and rigid wire or bands, and are pivoted to the top frame of the basket at spaced points to provide a sturdy support for the basket when carried, but are not otherwise attached to the bottom wall or flexible enclosing walls of the basket body and thus may be freely swung from and to carrying and collapsed positions.

In one form of this invention, the bottom wall of the receptacle is formed by flexible sheet material only, but the bottom wall is nevertheless maintained in relatively flat and taut condition when the basket is fully erected by the provision of a pair of stiffening rods or members secured to the receptacle body at the juncture between its flexible bottom wall and side walls. These paired stiffening rods extend substantially the length of the opposite sides of the receptacle body and cooperate with the transverse bottom stretcher parts of the supplemental frame assemblies to provide a discontinuous reinforcing frame structure for the bottom of the receptacle body. Additionally, the side stiffening rods maintain the bottom wall of the receptacle body in longitudinally extended position when the stretcher parts of the supplemental frame assemblies swing in contact with the bottom wall during the collapsing and erecting movements thereof. This feature assures smooth expansion and collapse of the receptacle body when the supplemental frame assemblies are manipulated, and prevents interference with the

2

swinging movement of the supplemental frame assemblies by any portion of the flexible material which forms the receptacle body. In this form of the invention, the handle part and stretcher part of each of the two supplemental frame assemblies may be advantageously formed as an integral unit from a U-shaped band or wire having inturned upper ends which are joined by a suitable hand grip element, and with the side legs of each U-shaped frame pivotally connected medially thereof to the top frame of the receptacle body. In this construction, the upper portions of the side legs and the connecting hand grip element of the U-shaped frame provide the handle part, and the lower portions of the side legs and the connecting bottom section of the frame provide the stretcher part which operates to maintain the receptacle body in rigidly erect position when the handle part is swung into juxtaposed basket carrying position.

In another form of this invention, the bottom wall of the receptacle body may be made relatively stiff and rigid by the provision of a liner platform of rigid material which may be removably seated on the bottom section of the flexible sheet material which defines the receptacle body. To adapt the supplemental frame assemblies for association with a receptacle body having a rigid bottom wall, the handle parts and the stretcher parts thereof are separately formed and separately pivoted to the top frame of the receptacle body. In this form of invention, each handle part is formed as a rigid U-shaped frame whose downwardly extending legs are pivotally connected to the top frame of the receptacle body. Each stretcher part is also formed from a rigid U-shaped frame having the upper ends of its legs separately pivoted to the top frame of the receptacle body at points exterior to the pivotal connection of the handle forming side legs with the top frame. The side legs of each handle part are provided with end extensions designed to project into the erected receptacle body and with the lower ends thereof pivotally and slidably connected to the upwardly extending side legs of the stretcher part at a point below their pivotal connection to the top frame. As thus assembled, the stretcher parts may be swung to positions substantially at right angles to the top frame and in bearing relation to the rigid liner platform to thereby maintain the receptacle body in rigidly erect position with the flexible side walls taut, when the paired handle parts are manipulated into juxtaposed basket carrying position. When the handle parts are manipulated into collapsed position, the associated stretcher parts will be swung thereby longitudinally with respect to the bottom wall into a position substantially parallel to the top frame of the receptacle body. Stop means are provided on the legs of each stretcher part which serve to fix the erected position of the stretcher parts and the carrying position of the handle parts.

Service baskets made in accordance with this invention provide carrying receptacles which are light in weight, strong and durable, and which can be manufactured at a relatively low cost to provide inexpensive, highly convenient, and space-saving portable containers for the accommodation of customers of self-service stores. These collapsible service baskets also find useful application in the home delivery of various kinds of merchandise, and as general utility baskets for use in homes, stores, and manufacturing and service establishments, as well as for the transportation of materials for picnics or other recreational purposes.

Other objects and advantages of this invention will become apparent as the disclosure proceeds.

Although the characteristic features of this invention will be particularly pointed out in the claims, the invention itself, and the manner in which it may be carried

out, may be better understood by referring to the following description taken in connection with the accompanying drawings forming a part hereof, in which:

Fig. 1 is a perspective view of a typical form of service basket constructed in accordance with this invention and as it would appear when fully erected into contents carrying position; the stretcher parts of the supplemental frame assemblies being shown in phantom lines;

Fig. 2 is a plan view of the erected service basket shown in Fig. 1;

Fig. 3 is a perspective view of the service basket shown in Figs. 1 and 2 as it would appear when fully collapsed;

Fig. 4 is a perspective view illustrating the framework structure for the basket shown in Figs. 1, 2 and 3 as the same would appear when in erected position with the flexible receptacle body removed therefrom, this view illustrating the relative positions of the top frame, the paired supplemental frame assemblies, and the bottom stiffening rods, when the basket of which they form a part is in fully erected position.

Fig. 5 is a side elevational view of one of the paired supplemental frame assemblies used in the basket shown in Figs. 1-3 and as the same would appear prior to pivotal attachment thereof to the top frame of the basket; this view also showing one of the side legs of the frame assembly in phantom lines and as it would appear prior to its insertion into the hand grip portion thereof;

Fig. 6 is an end view of the supplemental frame assembly shown in Fig. 5;

Fig. 7 is an enlarged side elevation detail showing the manner in which the side legs of each supplemental frame assembly is pivotally connected to the top frame of the receptacle body;

Fig. 8 is a side elevational view of the service basket shown in Figs. 1-3 and wherein the upper portions of the supplemental frame assemblies are shown in carrying position and the lower portions thereof in phantom lines; this view also showing in phantom lines the stretching effect produced on the bottom wall and end walls of the receptacle body during swinging movement of the supplemental frame assemblies to and from carrying position;

Fig. 9 is a perspective view of a modified form of improved service basket made in accordance with this invention, and which embraces a rigid bottom wall construction, this modification incorporating supplemental frame assemblies adapted for baskets having rigid bottoms;

Fig. 10 is a perspective view of the service basket shown in Fig. 9 as it would appear when fully collapsed;

Fig. 11 is a perspective view of the framing structure for the basket shown in Figs. 9 and 10 as the same would appear when fully erected with the flexible receptacle body removed therefrom;

Fig. 12 is a fragmentary perspective detail, showing the manner of pivotally mounting the handle part to the top frame of the basket;

Fig. 13 is a perspective view of a service basket similar to the basket shown in Figs. 9 and 10 but having its supplemental frame assemblies formed from stiff wire;

Fig. 14 is a perspective view illustrating the assembled framing structure for the basket shown in Fig. 13 as the same would appear when fully erected, the flexible receptacle body being removed to reveal the structural details thereof;

Fig. 15 is a side elevational view of the handle part of one of the two supplemental frame assemblies for the basket shown in Fig. 13 and as the same would be manufactured for pivotal assembly to the top frame of the basket one of the side legs of the handle part being shown detached from the hand grip portion thereof; and

Fig. 16 is a fragmentary elevational detail showing the manner in which the legs of the handle part of each supplemental frame assembly are pivotally connected to the top frame of the basket and pivotally and slidably connected to the legs of the body stretcher part thereof.

Similar reference characters refer to similar parts throughout the several views of the drawings and specification.

Service baskets constructed in accordance with this invention are preferably made substantially rectangular in horizontal section with the opposite sides thereof of any desired length but preferably longer than the width of the basket. The receptacle body 1 is formed of flexible sheet material such as hardwoven textile or flexible plastics and may conveniently comprise a flexible bottom forming section 2 whose side and end edges are secured to the bottom edge of a continuous band of flexible sheet material which presents a pair of side wall sections 3 and end wall sections 4. The band which forms the side and end wall sections may comprise a substantially rectangular strip whose ends 4' are stitched together to provide a strong and preferably double-stitched seam construction. The bottom edges of the side and end wall sections 3 and 4 of the continuous band, as thus formed, are also securely stitched to the corresponding side and end edges of the substantially rectangular bottom section 2 and in a manner to provide a beaded hem 5 extending around the bottom section 2.

The flexible receptacle body 1 is stiffened and braced at the upper top end thereof by a relatively rigid top frame 6 which is shaped to the desired contour of the basket. The top frame 6 is preferably formed of a continuous metal or plastic band of generally rectangular outline possessing sufficient stiffness to give the basket the desired strength and rigidity. The upper ends of the side and end wall sections 3 and 4 of the enclosing band are looped around the top frame 6 and secured as by stitching 7 to provide a closed tubular loop in which the top frame 6 is permanently contained.

In the embodiment of the invention shown in Figs. 1 through 8, the bottom wall section 2 and the side wall sections 3 of the flexible receptacle body 1 are maintained in longitudinally extended position by the provision of a pair of stiffening rods 8 which are secured along the lines of juncture between the bottom and side wall sections thereof. The stiffening rods 8 may be advantageously held in side stiffening position by forming the side portions of the beaded hem 5 in the form of a tubular loop of sufficient size to snugly receive and contain the stiffening rods 8 therein. The beaded hem 5 may be provided with a pair of end openings 5' at opposite corners thereof and through which the stiffening rods 8 may be inserted into the tubular bottom loops and thus held therein. The insertion openings 5' may thereafter be closed by stitching if desired to prevent any shifting of the stiffening rods within the tubular loops of the beaded hem.

The collapsible basket shown in Fig. 1 incorporates a pair of supplemental frame assemblies 9 each fabricated from relatively rigid metal or plastic wires or bands which are pivotally connected to the top frame 6 and which cooperate with the top frame 6 and the stiffening rods 8 to stretch the collapsible side walls of the receptacle body and maintain the same in rigidly erected position. In this construction the handle part *a* and the body stretcher part *b* of each supplemental frame assembly are integrally formed as a single U-shaped frame. Each of these U-shaped frames comprises a transverse bottom stretcher section 10, slightly shorter than the inside width of the bottom of the basket and adapted to bear against the bottom wall 2 for expanding the receptacle, and paired legs 11 extending upwardly from the bottom stretcher section 10 are formed with inturned upper ends 12, which are joined by a suitable wooden, plastic, or metal hand grip element 13. These inturned ends 12 may conveniently be secured to the hand grip element by knurling or ribbing a short section 14 of each end and pressing them into conforming bores in the ends of the hand grip elements.

A sturdy support for carrying the basket and for swingably mounting the supplemental frame assemblies for

erecting and collapsing the basket is provided by a simple pivotal connection of the paired legs 11 of each U-shaped frame to opposite sides of the top frame 6. This pivotal connection includes a clip 15 formed with a collar 15' encircling and tightly pressed around an offset section 11' medially of each leg 11. Ends 11" of the offset 11' firmly restrain the clip 15 against displacement along the leg 11, and a suitable rivet 16 pivotally secures the clip 15 to the top frame 6. This rivet 16 extends through a suitable inner washer 16' under the inner rivet head, through tabs 15" extending from the clip collar 15', through the top frame 6 and the flexible body material around the top frame, and an outer washer 16" under the outer rivet head. These pivotal mountings of the two supplemental frame assemblies are longitudinally spaced and secured to the top frame 6 about one-fourth the length of the basket from the end walls. This provides for ease in manipulating the handles by simply swinging them to and from carrying position and provides an overcenter latching of the stretcher part in the fully expanded position.

As the handle parts of the frame are swung through the center position perpendicular to the top frame, the bottom stretcher section 10 is brought to bear outwardly against the bottom wall 2 of the receptacle, extending it outwardly away from the top frame 6 further than the height of the receptacle side 3, as shown in phantom lines in Fig. 8. This is made possible by reason of a slight outward flare in the legs 11 and the shorter length of the transverse stretcher bottom section 10 than the width of the bottom wall 2. These features allow the stiffening rods 8 to move inwardly slightly towards each other during this operation and permit the outer edges of the bottom walls to extend downwardly to allow for deformation of the bottom wall without strain. In order further to minimize stress of the sheet material forming the receptacle body during this movement of the stretcher parts of the supplemental frame assemblies, the stiffening rods 8 are made slightly shorter than the length of the basket. This allows the bottoms of the end walls 4 to move slightly inwardly, as shown in phantom lines in Fig. 8, and further facilitates the outward deformation of the bottom wall. In addition, the flare of the side legs 11 of the frame assemblies helps prevent undue rubbing of these legs against the fabric of the side walls 3 and facilitates the swinging of the supplemental frame assemblies by avoiding interference between the two inner ends thereof in passing to and from their inner positions.

In the fully expanded position, the bottom stretcher sections 10 fit snugly into the junctures of the end walls 4 and the bottom wall 2, and pressure on any part of the receptacle body tends to force the stretcher sections 10 more firmly against the end walls. A positive swinging of the handles through their center positions is required in order to permit collapse of the receptacle. Thus, this mounting of the supplemental frame assemblies provides a simple arrangement for latching the frame structure in erected position and preventing undesirable accidental collapsing of the basket. The stiffening rods 8 maintain the configuration of the bottom wall 2 in longitudinally extended position and prevent interference of the flexible material of the bottom wall with the swinging movement of the stretcher parts of the frame assemblies. This assures smooth expansion and collapse and compact folding of the receptacle body. The simple mounting of the frame assemblies entirely on the top frame 6 and completely free of the bottom and the flexible sides of the basket provides a basket body having surfaces which are free of obstructions. This makes it possible conveniently to empty and to clean the inside of the basket.

Another form of this invention is illustrated in Figs. 9, 10, 11, and 12, in which the bottom wall of the receptacle body is made relatively rigid. In this basket, the flexible receptacle body has side and end walls formed

with upper portions which are connected to a top frame 6, as in the construction shown in Fig. 1. The bottom wall of the receptacle is made stiff by the provision of a liner platform 17 of thin, rigid, lightweight sheet material, such as plywood or hard sheet plastic, removably seated on the bottom section 2 of the flexible material forming the receptacle body.

In this rigid bottom type basket structure, a pair of supplemental frame assemblies is provided for erecting and carrying the basket. Each of these supplemental frame assemblies is formed in two separate handle and stretcher parts *a'* and *b'*, separately pivoted to the top frame 6. This separate structure is required in order to provide for relative lengthening and shortening of the distance between the transverse stretcher part bottom section and the pivotal mounting of the handle parts as the frame assemblies are swung between folded and erected positions. This is made necessary because the rigid bottom wall is not deformable, as in the basket shown in Fig. 1.

Each of these frame assemblies comprises a substantially U-shaped stretcher part *b'* having a transverse bottom stretcher section 18 and a pair of legs 19 extending upwardly therefrom. The stretcher parts *b'* are pivotally connected to the top frame 6 to provide for swinging them down to bear against the liner platform 17 for pressing it against the bottom wall 2 of the receptacle body, thereby to expand the side and end walls of the receptacle into fully erected position. This pivotal connection of the stretcher parts *b'* also provides for simply swinging them upwardly into positions within and substantially parallel to the top frame 6, leaving the receptacle body without support, so that it will collapse of its own weight and that of the supporting framework. A pivotal mounting for the stretcher part *b'* is conveniently provided by forming the ends of the paired legs 19 of the stretcher parts as eyes or loops 19' and pivotally mounting these ends of the paired legs of each stretcher part on opposite sides of the top frame at points spaced inwardly from the ends of the top frame and longitudinally spaced from the corresponding ends of the paired legs of the other stretcher part. The pivotal mounting includes a suitable rivet 20, which extends through an outer washer 21, the sheet material extending around the top frame 6, through an aperture in the top frame 6, the eye 19' at the upper end of the leg 19, and an inner washer 21'.

Expansion of the collapsible body of the basket is facilitated by forming the supplemental frame assemblies with U-shaped handle parts *a'*, each preferably made of a single band of relatively rigid material, such as metal or hard plastic. Each of these U-shaped handle parts *a'* is formed with a pair of legs 23 joined at their outer ends by a transverse hand grip section 24. These handle parts are pivotally mounted on the top frame 6 by suitably connecting each leg 23, intermediate the ends thereof, to opposite sides of the top frame at points spaced inwardly from the pivotal mountings of the eyes 19' of the stretcher part legs 19 and longitudinally spaced from the corresponding pivotal mountings of the legs of the other handle part. Each of these pivotal mountings of the legs 23 on the top frame 6 may conveniently comprise a suitable rivet 25, which extends through an outer washer 26, through the flexible body material around the top frame 6, through an aperture in the top frame 6, preferably through a spacing washer 27 arranged between the inner side of the top frame 6 and the adjacent side of the leg 23, through an aperture in the leg 23, and an inner washer 26'.

The handle part *a'* of each supplemental frame is operatively connected to its stretcher part *b'* such that when it is manipulated in one direction the hand grip sections 24 are brought into juxtaposed handle carrying position and the stretcher parts *b'* are brought into body expand-

ing and erecting position, and when manipulated in the opposite direction they permit collapse of the receptacle body. This connection of the handle part to the stretcher part is conveniently providing a pivotally and longitudinally slideable connection of the inner end of each of the handle part legs 23 to an intermediate section of the adjacent stretcher part leg 19 to provide a connection therewith which can be moved both pivotally relatively thereto and longitudinally slidably thereon. This pivotal and longitudinally slideable connection is formed by securing the inner end of each handle part leg 23 to a stretcher part leg 19 by a clip 28 having a collar 28' longitudinally slidably extending around an intermediate section of the stretcher part leg 19. Each clip 28 is formed with a pair of tabs 28" extending from its collar 28' and pivotally secured to the inner end of a handle part leg 23 by a suitable rivet 29, which extends through an outer washer 30, registering apertures in the clip tabs 28", an aperture in the end of the handle part leg 23, and an inner washer 30'.

Expansion of the receptacle body may be obtained simply by swinging the transverse hand grip sections 24 upwardly into close proximity with each other, as shown in Fig. 9. This manipulation of the handle parts *a'* causes the legs to swing downwardly and thereby to exert a force upon the intermediate section of the stretcher part legs 19. As a result, the transverse stretcher bottom sections 18 are swung downwardly into engagement with the liner platform 17 and cause it to bear against the flexible bottom wall 2, so as to expand the flexible body 1 of the basket while maintaining the rigid rectangular configuration of the bottom of the basket.

Each stretcher part leg 19 is formed with an angular offset projection 19", formed in the wire or other material comprising the leg 19, for limiting the upward longitudinal sliding movement of the clip 28 to a position which fixes the erected carrying position of the handle parts *a'* with the transverse hand grip sections 24 in juxtaposed basket carrying positions. This assures against accidentally swinging the hand grip sections of the supplemental frame assemblies past the carrying positions, which would result in an undesirable looseness or slack in the sheet material forming the sides and ends of the receptacle body. It also provides a completely self-contained handle frame assembly, free of all connections with the bottom and the flexible sides of the basket, so that it can be conveniently cleaned and emptied.

A compact folding of the supplemental frames is further assured by forming the handle part legs 23 slightly bowed inwardly, so that, in the collapsed position of the frame assemblies, there is clearance between the legs 23 and the pivotal mountings of the ends of the stretcher part legs 19. In addition, the lower ends of the stretcher part legs 19, adjacent the transverse stretcher section 18, are formed at an inwardly extending angle to the intermediate section thereof. This results in a close nesting of these ends around the ends of the other frame assembly when in collapsed position, as is best illustrated in Fig. 10. This provides a durable collapsible basket with a simple dual handle operated frame of sturdy construction for supporting and carrying the basket and for easy manipulation for expanding and collapsing the receptacle body.

A third embodiment of this invention is illustrated in the drawings in Figs. 13, 14, 15, and 16, in which the receptacle body is substantially the same as that shown in Figs. 1 and 9, and two supplemental two-part frame assemblies, similar to those shown in Figs. 9, 10, and 11, are provided for expanding the receptacle body and maintaining it erect. The bottom of the basket is made rigid by a relatively thin, lightweight rigid liner platform 16, and the stretcher parts *b'* of the supplemental frame are the same as in the basket shown in Figs. 9-11. This form of basket is primarily directed to providing a sturdy,

yet lighter weight, construction than that shown in Fig. 9. In the present construction, the supplemental frame assemblies are provided with U-shaped handle parts *a''* formed by rigid legs 32 of plastic or metal wires or bands, separately formed as shown in Fig. 14, with inturned upper ends 33 joined by transversely extending, relatively lightweight hand grip elements 34 of wood, hard plastic, or metal. The legs 32 of each handle part are securely fastened to one of the hand grip elements 34 in any suitable manner, which may conveniently include ribbed or knurled sections 33' of the inturned ends 33, pressed into conforming bores in the ends of a hand grip element 34.

In this construction, the legs are pivotally connected by any suitable means, as by clips 35, to the top frame 6, inwardly of the pivotal mountings of the stretcher parts. Each of these clips 35 is formed with a collar 35' tightly encircling an offset section 32' intermediate the ends of a leg 32. The ends of the offset section 32' serve to secure the clip against longitudinal displacement relative to the leg and securely fix its position. Tabs 35" extend from the collar 35' and are preferably bent slightly outwardly, so as to space the leg 32 from the adjacent side of the top frame 6 a distance about the thickness of a pair of clip tabs to provide for good alignment of the end of the leg 32 in its connection to the stretcher part. The clips 35 are each pivotally secured to the top frame 6 by a rivet 36, which extends through an outer washer 37, the flexible material around the top frame 6, an aperture in the top frame 6, the clip tabs 35", and an inner washer 37'.

Easy manipulation of the stretcher parts *b'* toward and away from the liner platform 17 for expanding and collapsing the receptacle body 1 is obtained by connecting the inner end of each leg 32 of the handle part *a''* pivotally and longitudinally slidably to an intermediate section of the adjacent leg 19 of the stretcher part of the frame assemblies. This pivotal and slideable connection comprises a clip 28 having a collar 28' longitudinally slidably fitted around an intermediate section of a stretcher leg 19 and having a pair of tabs 28" to which the inner end of the adjacent handle part leg 32 is pivotally secured. This inner end of each handle part leg 32 is conveniently formed as an eye or loop 32" which is pivotally secured to the clip tabs 28" by a pivot pin formed by a suitable rivet 38 extending through the eye 32", through registering apertures in the tabs 28", and through washers 39 under each rivet head.

With this construction, a simple swinging manipulation of the hand grip elements 34 into carrying position in close proximity to each other exerts a force upon the intermediate sections of the stretcher part legs 19 and swings the bottom transverse stretcher sections 18 downwardly against the liner platform 17, so as to press it away from the top frame 6 and thereby to expand the flexible receptacle body 1 while maintaining rigid the configuration of the bottom of the basket. Manipulation of the hand grip elements 34 away from each other and toward the top frame 6 and draws the stretcher part legs 19 in the same direction and away from the liner platform 17, leaving the flexible receptacle body without support, so that it collapses under its own weight and that of the framework.

Each stretcher part leg 19 is made with an angular offset projection 19" formed in the wire, or other material, comprising the leg 19 and functions, as in the construction shown in Figs. 9-12, to fix the erected position of the stretcher parts *b'* and the carrying position of the handle parts *a''* by fixing the topmost position to which the clips 28 can slide along the stretcher part legs 19.

Compactness of the collapsed basket is further assured by forming the handle part legs 32 bowed slightly inwardly between their pivotal mountings to the top frame 6 and their inturned outer ends 33 to provide a suitable clearance between the legs 32 and the pivotal mountings of the upper ends of the stretcher part legs 19 on the top frame 6. In addition, a compact folded assembly of the

framework of the basket; when in collapsed position, is further assured by forming the lower ends of the stretcher parts legs 19, adjacent the bottom transverse stretcher section 18, at a slight inwardly extending angle to the intermediate section thereof. This provides for closely nesting these ends around the ends of the other supplemental frame assembly when in collapsed position.

Service baskets constructed in accordance with this invention are particularly adapted and suited for use by customers in self-service stores, but have many other practical uses where strong and durable baskets of light weight are desired. The sturdy and convenient dual supplemental frame assemblies for expanding and collapsing the receptacle body of the basket make it especially practical where it is to be used by many different persons having many different habits of care and varying degrees of mechanical aptitude for manipulating the expandable framework of the basket. The arrangements for maintaining the configuration of the bottom wall of the receptacle in longitudinally extended position, including the stiffening rods and the liner platform, add greatly to the practicability of the baskets for use by the general public.

While certain novel features of this invention have been disclosed herein and are pointed out with particularity in the claims, it will be understood that various changes, modifications, substitutions, and omissions may be made by those skilled in the art without departing from the spirit and scope of this invention.

What is claimed is:

1. A collapsible service basket including in combination, a receptacle body presenting a bottom wall and flexible side and end walls connected to the peripheral portion of said bottom wall, rigid means for maintaining said bottom wall in longitudinally extended position, a relatively rigid top frame having side and end sections connected to the upper portions of said side and end walls of said flexible body, and a pair of supplemental frame assemblies each presenting a handle part having a hand grip section operatively connected to a stretcher part, said paired frame assemblies being pivotally connected in longitudinal spaced relation to said side sections of said top frame, said paired frame assemblies being operative when manipulated in one direction to bring said hand grip sections of the handle parts thereof into juxtaposed basket carrying position and the stretcher parts thereof into body expanding and erecting position and when manipulated in the opposite direction to permit collapse of the receptacle body.

2. A collapsible service basket including in combination, a receptacle body formed of flexible material presenting a bottom wall and enclosing side and end walls, rigid means for maintaining said bottom wall in longitudinally extended position, a relatively rigid top frame having side and end sections connected to the upper portions of said side and end walls, and a pair of supplemental frame assemblies each presenting a handle part having a hand grip section operatively connected to a stretcher part, said paired frame assemblies being pivotally connected in longitudinal spaced relation to said side sections of said top frame, said paired frame assemblies being operative when manipulated in one direction to bring said hand grip sections of the handle parts thereof into juxtaposed basket carrying position and the stretcher parts thereof into body expanding and erecting position and when manipulated in the opposite direction to permit collapse of the receptacle body.

3. A collapsible basket including in combination, a receptacle body presenting a bottom wall and collapsible side and end walls connected to the corresponding peripheral portions of said bottom wall, said bottom wall incorporating means for maintaining the same in longitudinally extended position, a relatively rigid top frame having side and end sections connected to the upper portions of said side and end walls of said receptacle body, a pair of supplemental frame assemblies each presenting a handle

part operatively connected to a substantially U-shaped stretcher part, each of said stretcher parts presenting a transverse section and a pair of legs extending therefrom, and means for pivotally connecting said paired legs of said stretcher parts to opposite side sections of said top frame in paired and longitudinally spaced relation, said stretcher parts being operative when manipulated in one direction to stretch said side and end walls from collapsed to erected position and when manipulated in the opposite direction to permit collapse of said side and end walls of the receptacle body.

4. A collapsible service basket including in combination, a receptacle body formed of flexible sheet material presenting a bottom wall and enclosing side and end walls, rigid means for maintaining said bottom wall in longitudinally extended position, a relatively rigid top frame having side and end sections connected to the upper portions of the corresponding side and end walls of said receptacle body, a pair of supplemental frame assemblies, each presenting a handle part having a hand grip section and a stretcher part operatively connected to said handle part, each of said stretcher parts having a transverse section and a pair of legs extending therefrom, and means for pivotally connecting said paired legs of both stretcher parts in paired and longitudinally spaced relation to said side sections of said top frame, said paired frame assemblies being operative when manipulated in one direction to bring said hand grip sections of the handle parts thereof into juxtaposed basket carrying position and the stretcher parts thereof into body expanding and erecting position and when manipulated in the opposite direction to permit collapse of said receptacle body.

5. A collapsible service basket including in combination, a receptacle body presenting a bottom wall and collapsible side and end walls, rigid means for maintaining said bottom wall in longitudinally extended position, a relatively rigid top frame having side and end sections connected to the upper portions of said side and end walls of said receptacle body, a pair of supplemental frame assemblies each presenting a handle part having a hand grip section and a stretcher part operatively connected to said handle part, said stretcher part having transverse bottom and side stretcher sections which are longitudinally movable with respect to said bottom wall, and two pairs of pivoting means mounted on said side sections of said top frame, said pivoting means being longitudinally spaced with respect to each other and spaced inwardly a distance approximating one-fourth the length of the basket from the adjacent end walls thereof, said pivoting means being operative to pivotally connect said paired frame assemblies to said side sections of said top frame, said paired frame assemblies being operative when manipulated in one direction to bring said hand grip sections of the handle parts thereof into juxtaposed basket carrying position and the stretcher parts thereof into body expanding and erecting position and when manipulated in the opposite direction to permit collapse of the receptacle body.

6. A collapsible service basket including in combination, a receptacle body formed of flexible material presenting a bottom wall and enclosing side and end walls, rigid means for maintaining said bottom wall in longitudinally extended position, a relatively rigid top frame having side and end sections connected to the upper portions of said side and end walls of said receptacle body, a pair of supplemental frame assemblies each presenting a handle part having a hand grip section and a stretcher part operatively connected to said handle part, said stretcher part having transverse bottom and side stretcher sections which are longitudinally movable with respect to said bottom wall, and two pairs of pivoting means mounted in longitudinally spaced relation with respect to each other on said top frame and spaced inwardly a distance approximating one-fourth the length of the basket from the adjacent end walls thereof, said pivoting means being operative to pivotally connect the paired frame assemblies to said side

sections of said top frame, said paired frame assemblies being operative when manipulated in one direction to bring said hand grip sections of the handle parts thereof into juxtaposed basket carrying position and the stretcher parts thereof into body expanding and erecting position in an overcenter latched position with said transverse bottom sections thereof in engagement with said receptacle body adjacent the junctures of said end and bottom walls and when manipulated in the opposite direction to permit collapse of said receptacle body.

7. A collapsible service basket including in combination, a receptacle body formed of flexible sheet material presenting a bottom wall and enclosing side and end walls, rigid means for maintaining said bottom wall in longitudinally extended position, a relatively rigid top frame having side and end sections connected to the upper portions of said side and end walls of said receptacle body, a pair of supplemental frame assemblies each presenting a handle part having a hand grip section and a U-shaped stretcher part operatively connected to said handle part, each of said stretcher parts presenting a transverse bottom stretcher section and a pair of legs flaring outwardly therefrom, said paired frame assemblies being pivotally connected in longitudinal spaced relation to said side sections of said top frame, said paired frame assemblies being operative when manipulated in one direction to bring said hand grip sections of the handle parts thereof into juxtaposed basket carrying position and the stretcher parts thereof into body expanding and erecting position and when manipulated in the opposite direction to permit collapse of said receptacle body, the transverse bottom stretcher sections of said stretcher parts being shorter than the transverse width of said bottom wall whereby stress on the flexible receptacle body is minimized during manipulation of said frame assemblies.

8. A collapsible service basket including in combination, a receptacle body formed of flexible sheet material presenting a bottom wall and enclosing side and end walls, rigid means including a pair of stiffening rods mounted along the junctures of said side walls and said bottom wall for maintaining said bottom wall in longitudinally extended position, a relatively rigid top frame having side and end sections connected to the upper portions of said side and end walls of said receptacle body, and a pair of supplemental frame assemblies each presenting a stretcher part, said paired frame assemblies being pivotally connected in longitudinal spaced relation to said side sections of said top frame, said paired frame assemblies being operative when manipulated in one direction to bring the stretcher parts thereof into body expanding and erecting position and when manipulated in the opposite direction to permit collapse of said receptacle body.

9. A collapsible service basket including in combination, a receptacle body presenting a bottom wall and collapsible side and end walls, rigid means including a pair of stiffening rods mounted along the junctures of said side walls and said bottom wall for maintaining said bottom wall in longitudinally extended position, a relatively rigid top frame having side and end sections connected to the upper portions of said side and end walls of the receptacle body, and a pair of supplemental frame assemblies each presenting a handle part having a hand grip section and a stretcher part operatively connected to said handle part, said paired frame assemblies being pivotally connected in longitudinally spaced relation to said side sections of said top frame, said paired frame assemblies being operative when swung in one direction to bring said hand grip sections of the handle parts thereof into juxtaposed basket carrying position and the stretcher parts thereof into body expanding and erecting position and when swung in the opposite direction to permit collapse of said receptacle body.

10. A collapsible service basket including in combination, a receptacle body formed of flexible sheet material

presenting a bottom wall and enclosing side and end walls, means including a pair of stiffening rods mounted along the junctures of said side walls and said bottom wall for maintaining said bottom wall in longitudinally extended position, a relatively rigid top frame having side and end sections connected to the upper portions of the side and end walls of the receptacle body, a pair of supplemental frame assemblies each presenting a handle part having a hand grip section and a U-shaped stretcher part operatively connected to the handle part, each of said stretcher parts presenting a transverse bottom stretcher section and a pair of legs extending outwardly therefrom, said paired frame assemblies being pivotally connected in longitudinal spaced relation to the side sections of said top frame, said paired frame assemblies being operative when manipulated in one direction to bring the hand grip portions of the handle parts thereof into juxtaposed basket carrying position and the stretcher parts thereof into body expanding and erecting position, and when manipulated in the opposite direction to permit collapse of the receptacle body, said transverse bottom stretcher sections of said stretcher parts being shorter than the transverse width of said bottom wall and said paired legs flaring outwardly therefrom whereby stress on the flexible receptacle body is minimized during manipulation of said frame assemblies.

11. A collapsible service basket including in combination, a receptacle body formed of flexible sheet material presenting a bottom wall and side and end walls, a relatively rigid sheet liner removably seated on said bottom wall, a relatively rigid top frame connected to the upper portions of said side and end walls, a pair of supplemental frame assemblies each having a handle part with a hand grip section and a stretcher part, and means for pivotally connecting said supplemental frame assemblies in longitudinally spaced relation to said top frame, said paired frame assemblies being operative when manipulated in one direction to place said hand grip sections in juxtaposed basket carrying position and to press said stretcher parts against said rigid sheet liner for thereby expanding said receptacle body and when manipulated to move said hand grip sections away from each other and toward said end walls to permit collapse of said receptacle side and end walls.

12. A collapsible service basket including in combination, a receptacle body formed of flexible sheet material presenting a bottom wall and enclosing side and end walls, means including a relatively rigid sheet liner seated on said bottom wall for maintaining said bottom wall in longitudinally extended position, a relatively rigid top frame having side and end sections connected to the upper portions of the side and end walls of said flexible body, and a pair of supplemental frame assemblies each presenting a handle part having a hand grip section and being operatively connected to a stretcher part, said paired frame assemblies being pivotally connected to the side sections of said top frame in longitudinal spaced relation, said paired frame assemblies being operative when manipulated in one direction to bring the hand grip sections of the handle parts thereof into juxtaposed basket carrying position and the stretcher parts thereof into body expanding and erecting position and when manipulated in the opposite direction to permit collapse of the receptacle body.

13. A collapsible service basket including in combination, a receptacle body formed of flexible sheet material presenting a bottom wall and side and end enclosing walls, a rigid sheet liner seated on said bottom wall, a rigid top frame having side and end sections connected to the upper portions of said end and side enclosing walls, a pair of supplemental frame assemblies each having a substantially U-shaped stretcher part with a transverse bottom section and a pair of legs extending therefrom, means for pivotally connecting the ends of each paired stretcher part legs on opposite side sections of said top

frame in longitudinally spaced relation to the pivotal connections of the other paired stretcher part legs; said paired frame assemblies being operative when manipulated in one direction to bring the stretcher parts thereof into body expanding and erecting position and when manipulated in the opposite direction to permit collapse of said receptacle body.

14. A collapsible service basket including in combination, a receptacle body formed of flexible sheet material presenting a bottom wall and enclosing side and end walls, a relatively rigid sheet liner seated on said bottom wall, a relatively rigid top frame having side and end sections connected to the upper portions of said side and end walls, a pair of supplemental frame assemblies each presenting a handle part having a hand grip section and a stretcher part, said paired frame assemblies being pivotally connected in longitudinally spaced relation to the side sections of said top frame providing for expanding said receptacle body by manipulation of said supplemental frame assemblies in one direction to bring said hand grip sections into juxtaposed basket carrying position and said stretcher parts into body expanding position and when manipulated in the opposite direction to permit collapse of said receptacle body, and stop means on each of said supplemental frame stretcher parts for limiting movement of said hand grip sections towards each other to the predetermined juxtaposed carrying position.

15. A collapsible service basket including in combination, a receptacle body formed of flexible material and presenting a bottom wall and side and end enclosing walls, a rigid top frame having side and end sections connected to the upper portions of said side and end enclosing walls respectively, a pair of supplemental frame assemblies, each of said supplemental frame assemblies having a substantially U-shaped stretcher part with a transverse bottom section and a pair of legs extending therefrom, means for pivotally connecting paired stretcher part legs on opposite side sections of said top frame in longitudinally spaced relation to the pivotal connections of the other paired stretcher part legs, said supplemental frame assemblies each having a substantially U-shaped handle part formed with a hand grip section and a pair of legs extending therefrom, means for pivotally connecting said handle part legs intermediate the ends thereof to said top frame side sections adjacent to and spaced inwardly from said stretcher part leg pivotal connections, and means for connecting the inner end of each of said handle part legs pivotally and longitudinally slidably to an intermediate section of the stretcher part leg adjacent thereto, said paired frame assemblies being operative when manipulated in one direction to place said hand grip sections in juxtaposition and said stretcher parts into body expanding position and when manipulated in the opposite direction to permit collapse of said receptacle body, the lower ends of said stretcher part legs beyond the intermediate section thereof extending angularly inwardly for more compactly collapsing said receptacle body.

16. A collapsible service basket including in combination, a receptacle body formed of flexible sheet material presenting a bottom wall and enclosing side and end walls, means including a relatively rigid sheet liner seated on said bottom wall for maintaining said bottom wall in longitudinally extended position, a relatively rigid top frame having side and end sections connected to the upper portions of the side and end walls of said flexible body, and a pair of supplemental frame assemblies each having a handle part with a hand grip section and an U-shaped stretcher part with a transverse bottom section and a pair of legs extending therefrom, means pivotally mounting the ends of each pair of said stretcher part legs on opposite side sections of said top frame in longitudinally spaced relation to the pivotal mounting of the other pair of said stretcher part legs, means pivotally connecting each of said handle parts on said top frame

longitudinally spaced between the other to said handle part pivotal connecting means and one of said stretcher leg pivotal mountings, means pivotally and longitudinally slidably connecting each of said handle parts to an intermediate section of the adjacent stretcher leg, said paired frame assemblies being operative when swung in one direction to bring said hand grip sections of the handle parts thereof into juxtaposed basket carrying position and the stretcher parts thereof into body expanding and erecting position and when swung in the opposite direction to permit collapse of the receptacle body, the lower ends of said stretcher part legs beyond said intermediate sections thereof extending angularly inwardly therefrom for more compactly collapsing said receptacle body.

17. A collapsible service basket including in combination, a receptacle body formed of flexible sheet material presenting a bottom wall and enclosing side and end walls, means including a relatively rigid sheet liner seated on said bottom wall for maintaining said bottom wall in longitudinally extended position, a relatively rigid top frame having side and end sections connected to the upper portions of the side and end walls of said flexible body, and a pair of supplemental frame assemblies each presenting a handle part having a hand grip section and a substantially U-shaped stretcher part with a transverse bottom section and a pair of legs extending therefrom, means for pivotally mounting the ends of the paired stretcher part legs on opposite side sections of said top frame in longitudinally spaced relation to the pivotal mountings of the other paired stretcher part legs, means for operatively connecting said handle parts to said stretcher part legs, said paired frame assemblies being operative when swung in one direction to bring the stretcher parts thereof into body expanding and erecting position and when swung in the opposite direction to permit collapse of the receptacle body, stop means on said stretcher part legs for limiting the swing of said frame assemblies in the basket erecting direction to a position with said hand grip sections in juxtaposed basket carrying positions.

18. A collapsible service basket including in combination, a receptacle body formed of flexible sheet material presenting a bottom wall and enclosing side and end walls, means including a relatively rigid sheet liner seated on said bottom wall for maintaining said bottom wall in longitudinally extended position, a relatively rigid top frame having side and end sections connected to the upper portions of the side and end walls of said flexible body, and a pair of supplemental frame assemblies each presenting a substantially U-shaped handle part and a substantially U-shaped stretcher part, said stretcher part having a transverse bottom section and a pair of legs extending therefrom, means for pivotally mounting the ends of said paired stretcher part legs on opposite side sections of said top frame in longitudinally spaced relation to the pivotal mounting of the other of said stretcher part legs, said handle part having a transverse hand grip section and a pair of legs extending therefrom, means for pivotally connecting said handle part legs intermediate the ends thereof to opposite side sections of said top frame longitudinally spaced between the other of said handle part pivotal connecting means and one of said stretcher part leg pivotal mountings, means for pivotally and longitudinally slidably connecting the end of each handle part leg to an intermediate section of the adjacent stretcher part leg, said paired frame assemblies being pivotally connected in longitudinal spaced relation to the side sections of said top frame, said paired frame assemblies being operative when swung in one direction to bring said hand grip sections of the handle parts thereof into juxtaposed basket carrying position and the stretcher parts thereof into body expanding and erecting position and when swung in the opposite direction to permit collapse of the receptacle body, stop means on each of said stretcher part legs formed by an angular offset projection

for limiting the upward sliding movement of said pivotal and slidable handle part leg connecting means thereon to a position wherein said hand grip sections are in the juxtaposed basket carrying positions.

19. A collapsible service basket including in combination, a receptacle body formed of flexible sheet material presenting a bottom wall and enclosing side and end walls, means including a relatively rigid sheet liner seated on said bottom wall for maintaining said bottom wall in longitudinally extended position, a relatively rigid top frame having side and end sections connected to the upper portions of the side and end walls of said flexible body, and a pair of supplemental frame assemblies each presenting a substantially U-shaped handle part and a substantially U-shaped stretcher part having a transverse bottom section and a pair of legs extending therefrom, means for pivotally connecting the ends of said paired stretcher part legs to opposite side sections of said top frame in longitudinally spaced relation to the pivotal connections of the other of said paired stretcher part legs, said substantially U-shaped handle part having a hand grip section and a pair of legs extending therefrom, means for

5 pivotally connecting said paired handle part legs intermediate the ends thereof to opposite side sections of said top frame, said pivotal connecting means for each paired handle part legs being longitudinally spaced between the other of said handle part leg pivotal connecting means and one of said stretcher part leg pivotal connections, and means for connecting the end of each handle part leg pivotally and longitudinally slidably to an intermediate section of the adjacent stretcher part leg, said paired frame assemblies being operative when swung in one direction to bring said hand grip sections of the handle parts thereof into juxtaposed basket carrying position and the stretcher parts thereof into body expanding and erecting position and when swung in the opposite direction to permit collapse of the receptacle body.
